George W. Tolhurst

UNITED STATES PATENT OFFICE.

GEORGE W. TOLHURST, OF LIVERPOOL, OHIO.

WASHING-MACHINE.

Specification of Letters Patent No. 25,455, dated September 13, 1859.

To all whom it may concern:

Be it known that I, GEORGE W. TOLHURST, of Liverpool, in the county of Medina and State of Ohio, have invented a new and 5 useful Improvement in Machines for Washing Clothes; and I do hereby declare that the following is a full and exact description thereof, reference being had to the accompanying drawings and to the letters of reference marked thereon.

10 The nature of my invention consists in providing the inside of a washing machine with a second bottom or inside box, made airtight and constructed so as to float the 15 articles to be operated for the purpose of soaping arranging and examining them.

Figure 1, an end view showing the clothes submerged by the rubber ready for operation. Fig. 2, an end view showing the 20 clothes brought to the top of the water for inspection.

To enable others skilled in the art to make and use my invention, I will proceed to describe its construction and operation.

25 I construct the outside portion of my machine oblong, square at the ends as seen at A, A, Figs. 1, and 2.

B, is a box made airtight on sides and top, the top being furnished with slats made sharp at the upper edge as seen at, b.

30

C, is the clothes in process of being rubbed.

D, is the rubber, which rocks on the pivot, E, Fig. 1, in the grooves, F, Fig. 2.

H Fig. 1, is a lever "or handle" by which the rubber, D, is operative.

35

I, is a cord which is secured to one side of the outside box at one end and passed over a notch in the end of the handle and drawn tight over and wound around a screw on the other side of the outside box for the 40 purpose of taking the upper pressure from the hand of the operator.

J, Figs. 1, and, 2, represents the water.

Having thus described my improved washing machine what I claim as new and desire 45 to secure by Letters Patent is—

The inside bottom box B, constructed airtight so that when the pressure of the upper rubber is removed it will float and expose the clothes to be handled.

GEO. W. TOLHURST.
